CLAIM

The ornamental design for a display screen with icon, as shown and described.

DESCRIPTION

The file of this patent contains at least one drawing/photograph executed in color. Copies of this patent with color drawing(s)/photograph(s) will be provided by the office upon request and payment of the necessary fee.

The FIGURE is a front view of a display screen with icon showing my new design.

The broken line in the FIGURE showing the display screen is for environmental purposes only and forms no part of the claimed design.

1 Claim, 1 Drawing Sheet
(1 of 1 Drawing Sheet(s) Filed in Color)
